UNITED STATES PATENT OFFICE.

ROBERT L. DORAN, OF CHICAGO, ILLINOIS.

AUTOMATIC SHUT-OFF DEVICE FOR OIL BURNERS.

Application filed October 14, 1925. Serial No. 62,420.

This invention relates to improvements in oil furnaces, more particularly to safety shut-off devices for the same and especially for such devices operable by an accumulation of unburned fuel.

The chief characteristics are a tilting lever having a receptacle into which the oil is drained from the burner and having a mercury position operated motor switch device mounted thereon, a weight adapted to be rotated into disengagement with a supporting pin by the said lever, and a weighted shut-off valve. This valve being normally propped open by a projection on a trigger lever which is moved to allow the valve to close by the falling weight when a small amount of oil has collected in the lever receptacle to release the weight by tilting the lever. The invention also includes special means for safeguarding against broken springs.

Heretofore safety shut-offs have been operated by a weight released by an accumulation of unburned oil in which spring pressed supports were released for withdrawal from supporting the weight, and other like methods which required considerable power to operate and usually the shut-off was accomplished by allowing the main control valve of the device to move to closed position.

The main objects of this invention are to provide an automatic shut-off which is more sensitive and positive in its operation, which requires less power to release the motor element, which may function entirely independent of all springs, which is simple and substantial in its construction, which is readily set and sure in its action. Also to provide a device which automatically shuts off both the blower motor and the oil supply.

An illustrative embodiment of my invention is shown in the accompanying drawings, in which:

Figure 1 is a side elevation of the portion of the furnace including the controlling and operation mechanism.

Fig. 2 is a plan view of a portion of Figure 1.

Fig. 3 is taken on line 3—3 of Figure 1.

Fig. 4 is a larger scale section of the valve taken on line 4—4 of Fig. 2 with the outlet connection shown as if located in the same plane, with the valve in closed position.

Figure 5 is a fragmental view showing

the relation between the end of the trigger and the lower end of the plunger, shown in the lower part of Figure 4 and other figures.

Fig. 6 is a view similar to Fig. 5 showing the same parts in the normal position with the shut-off valve held open.

Fig. 7 is a section on line 7—7 of Fig. 3.

Fig. 8 is a section on line 8—8 of Fig. 3.

Fig. 9 is a section on line 9—9 of Fig. 3.

As shown in the drawings the shut-off device 10 is inserted in the oil supply line 11 ahead of the usual control valve which is mounted in the housing 12 from which the oil passes through the pipe 13 to the burner which is not shown, but could be like the burner shown in my Patent No. 1,559,559, November 3, 1925.

At the burner the oil is ignited and a high rate of combustion is supported by a forced draft supplied by the blower 14 operated by the motor 15. In case the oil is not burned as fast as it is fed into the burner or in case the flame is entirely extinguished the oil drains from the burner through the pipe 16 and collects in the bucket or receptacle 17 which is suspended from one arm of the pivoted lever 18.

The lever 18 is pivoted on the frame member 19 which is attached to the base frame 20 supported by the standard 21, and is provided with a crank pin 22 having a ball terminal which is adapted to engage in the vertical groove 23 in the outer surface of the cylindrical weight 24 which slides on the vertical rod 25 mounted in the frame 19.

In setting, the weight 24 is raised on the rod 25 with the slot or groove 23 registered with the stop pin 26 conveniently formed by an extension of the pivot member 27 and which passes freely through the groove 23. Then lever 18 is rotated so that the crank pin 22 is in line with the stop pin 26, whereupon the weight is raised above the stop pin 26 and rotated so that the weight rests on the stop 26 with the crank pin 22 engaged in the slot. With the bucket 17 empty the friction of the weight on the stop 26 holds the arm 18 in the corresponding set position in which the lever 18 is closely balanced by means of the weight 27 which is held in position on the weight arm 28 between the threaded nuts 29.

When oil collects in the bucket 17, the arm 18 rotates and, through the crank pin 110

connection, turns the weight until the slot 23 registers with the pin 26 and releases the weight.

In falling, the weight strikes the trigger lever 30 which has one end positioned in the path of the weight and is pivotally mounted on the yoke 31 which is secured to the valve housing 32 of the shut-off 10.

The housing 32 is provided with a transverse partition 33 forming upper and lower chambers which are connected by the valve passage 34, centrally located in 33. The valve 35 is vertically guided in the upper chamber by the periphery of the valve weight 36 which is secured to the stem of the valve 35 and in which is seated a valve closing spring 37 bearing against the top plate 38. Since the oil is admitted into the upper chamber through the supply pipe 11, the effective oil pressure on the area of the passage 34 together with the weight and the spring urge the valve 35 downwardly to close the passage 34, to the shut-off position shown in Fig. 4.

Normally the valve 35 is propped open by lifting the trigger lever 30 so that the ball 39, carried by 30, raises the plunger 40 which engages in the shallow recess in the chamfered nut 41 locked on the lower end of the plunger 40. The plunger is guided in the member 31 and stopped from falling through by the flange portion 42. In the released position the upper end of 40 clears the diaphragm nut 43, secured in the diaphragm 44 which closes the end of the lower chamber; and inner end of the nut 43 clears the lower end of the projection 45 of the valve 35 thus allowing the valve to seat.

When the plunger 40 is raised the contacts are made and the valve is held up to open the passage 34 to the lower chamber and allow the oil to flow through the passage 46 and through the pipe 47 into the control valve housing 12 which regulates the oil flow to the burner.

As mentioned above and shown in Fig. 6, the ball 39 engages in the lower end of the plunger member 41 and since pressure is being exerted downwardly by the weight 36 and the spring 37, the lever 30 is thereby held in set position. In case the spring 37 should fail and the load of the weight 36 should not be sufficient to hold the trigger lever 30 set, a safety gravity operated latch 48 is provided. The latch 48 is pivotally suspended from the frame 19 and has a finger 49 which underlies the projection 50 of the trigger lever 30. When the weight 24 falls it strikes the projecting portion of the latch 48 and throws the finger 49 out of the way before striking the lever 30, which is struck with a force sufficient to overcome the restraining movement of the ball engagement and release the valve 35 for closing.

When the lever 18 is rotated to release the weight 24, the supply circuit of the motor 15 is also opened by means of the mercury switch 51. The switch 51 is mounted on the weight arm of the lever 18 in tilted position so that when the lever is set the motor circuit leads 52 are connected and when the lever is rotated to off position the connection is broken.

While but one illustrative embodiment has been shown many omissions and alterations may be made without departing from the spirit of the invention.

I claim:

1. A construction of the class described having an oil supply valve, a safety shut-off comprising,—a stop, a slidably mounted weight normally rotated to rest on said stop and adapted on being released to close the valve, and means operable by an accumulation of unburned fuel for rotating said weight relative to the stop for releasing the same from the stop.

2. In a construction of the class described, valve operating means comprising a stop, a slidably mounted weight adapted to operate the valve having projecting portions and adapted to be rotated to engage the projecting portions with the stop for holding the weight in inoperative position, and means for rotating the weight to disengaged position for releasing for operating the valve.

3. In a construction of the class described, a valve having an operating lever and a stop, a weight suspended over the lever and held by being rotated into engagement with said stop, and means for rotating the weight for disengagement with the stop thereby allowing the weight to fall onto the said lever to operate the valve.

4. In combination in an oil furnace, an automatically closing valve, means normally holding the valve open having an operating lever, a stop member, a weight slidably mounted on the lever and held by projecting portions of the weight being rotated into engagement with said stop member, and means for rotating the weight to move said projecting portions out of engagement with the stop thereby releasing the weight to impinge the lever to release and allow the valve to close.

5. In combination in an oil furnace, an automatically closing valve, means normally holding the valve open having an operating lever, a stop member, a weight slidably mounted on the lever and held by projecting portions of the weight being rotated into engagement with said stop member, and means operable by an accumulation of unburned fuel for rotating the weight to move said projecting portions out of engagement with the stop thereby releasing the weight to impinge the lever to release and allow the valve to close.

6. In a construction of the class described having a shut-off valve, releasable means for operating said valve comprising a stop, a weight slidably guided in relation to the stop and having a groove in the edge adapted to register with the stop, a pivoted balance arm having a crank pin engaging in said groove for rotating the weight when in position above the stop, and means operable by an accumulation of unburned fuel for rotating said balance arm.
7. In combination in an oil furnace a gravity-closed shut-off valve, a trigger for propping the valve open, and a weight releasable by an accumulation of unburned fuel for dislodging the trigger to allow the valve to close, and a latch operable by the released weight normally retaining the trigger in set position.
8. In combination in an oil furnace, an automatically closing valve, a trigger member adapted to be set to hold the valve open, a stop, a slideable weight having outstanding portions adapted to be rotated into engagement with the stop, a balance lever having a crank pin in slidable engagement with the weight adapted to rotate said portions out of engagement with said stop, and means for moving the balance lever.
- Signed at Chicago this 12th day of October, 1925.

ROBERT L. DORAN.
